CLAIM

The ornamental design for an exercise ball, as shown and described.

DESCRIPTION

FIG. 1 is a front perspective view of an exercise ball.

FIG. 2 is a front view thereof.

FIG. 3 is a rear view thereof.

FIGS. 4 and 5 are opposing side views thereof.

FIG. 6 is a top view thereof; and,

FIG. 7 is a bottom view thereof.

The broken lines shown in the figures are for the purpose of illustrating portions of the exercise ball, which form no part of the claimed design.
